United States Patent Office.

CYRUS W. SALADEE, OF NEWARK, OHIO.

Letters Patent No. 70,903, dated November 12, 1867.

IMPROVEMENT IN DOOR-SPRINGS.

The Schedule referred to in these Letters Patent and making part of the same.

TO ALL WHOM IT MAY CONCERN:

Be it known that I, CYRUS W. SALADEE, of Newark, county of Licking, State of Ohio, have invented a new and improved Mode of Constructing Springs for Closing Doors and Gates; and I do hereby declare that the following is a full and exact description thereof, reference being had to the accompanying drawings and to the letters of reference marked thereon.

The nature of my invention consists—

First. In the peculiar arrangement hereinafter shown and described, of connecting the arm B to the head of the mandrel C, figs. 1 and 2, plate 1, for the purpose of regulating the tension of the spring.

Second. In that of securing the end of the arm B to the door or gate, by means of a stirrup, F F, jointed to the end of the arm, in such manner as to discard the use of the friction-roller generally applied to the outer end of the arm to operate against the door or gate, and in such manner that the end of the arm may be instantly disengaged from the stirrup, or its equivalents, connecting it to the door, as hereinafter shown and described.

Third. In that of bending the butt end of the arm in such manner as to allow the door to swing back against the partition or wall in which the door-frame is set, when the spring is applied in such manner as to pull the door or gate shut, in place of pushing it shut. And I will here state that by this arrangement of the straight arm B, as shown on plate 1, and the bent arm on plate 2, I am enabled to either push the door or gate shut, or by placing the box A upon the side of the frame J, as shown on plate 2, pull it shut.

In the drawings—

Figure 1, plate 1, is a complete view of the spring, with straight arm when applied so as to push the door; and

Figures 1 and 2, plate 2, represent the same with bent arm, and applied in such manner as to pull the door or gate.

Figure 2, plate 1, is a top view of the box or casing A, with the top broken off so as to expose the arrangement of the spiral spring E, mandrel C, collar K, and plate I, and the head C' of the mandrel C, a piece of the arm B, and the nut or tap D, holding the arm in position.

Figure 3 is an end view in section of the box or casing A, spiral spring E, and mandrel C, arm B in position, and the stirrup F F connecting the outer end B' to the door or gate.

The construction and operation of my complete door and gate-spring are substantially as follows: The box or casing A is formed as shown in the drawings, or may be of any other design which the fancy may suggest. The mandrel C is made to extend the full length of the box A, and the upper end of the mandrel is provided with the collar K, or its equivalent, (see fig. 2,) for the purpose of receiving and holding the upper end of the spiral spring E, and is finished by forming the head C' so as to make a tenon to receive the butt end of the arm B. This tenon may be square, or any other form that will answer the purpose, (see o o o o, figs. 1 and 2,) and in the end of this tenon is cast a small pin upon which is cut a thread to receive the acorn-shaped tap or nut D, which holds the arm B in position on the mandrel, as shown. In the lower or rear end of the box A, I fit the loose plate I, which is about three-sixteenths of an inch thick, and conforming in shape to the inside of the box, and through the centre of which is pierced the hole to receive the lower end of the mandrel C. This plate I is also made to serve for the fastening of the lower end of the spiral spring E. The arm B, I make in two ways: When the box A is applied to the casing of the door, or hinge part of the gate, on the side to which the door or gate opens, so as to push it shut, I use the straight arm shown on plate 1. But when the box A is secured to the inside of the casing of the door or post of the gate, as shown on plate 2, so as to pull the door or gate shut, the arm is bent at or near the end secured to the mandrel, so as to admit of the door being thrown wide open. I thus have the double advantage, in one and the same spring, of either pushing or pulling shut the door or gate. This, I claim, is a new feature in springs used for this purpose, and gives a decided advantage in its application; for if the finish of the casing of the door or gate on the side to which it swings is such as to forbid the application of the box A, as shown on plate 1, to push the door, I can then resort to the bent arm, shown on plate 2, and place the box A on the casing on the opposite side of the door and pull the door shut, as will be seen by reference to plate 2 of the drawings. The butt end of the arm B has a hole pierced through it to correspond with the shape and size of the tenon on the top end of the mandrel C, and is secured in its position by the nut or tap D, shown on plate 1. The outer end of the arm B may be secured to the door, when

used to pull it shut, by means of a friction-roller and guide, as shown by figs. 1 and 2, plate 2. But as by this operation the friction-roller has a tendency to make considerable noise, I prefer making this connection by means of the joints 7 and 9, figs. 1 and 3, plate 1, and the stirrup F F, substantially as shown. This arrangement of securing the outer end B¹ of the arm to the door or gate, possesses at once two very important advantages over that of any other known device for doing the same, viz: first, by the interposition of this stirrup F F, working upon the two pivot-joints 7 and 9, one end of the stirrup connected to the end B¹ of the arm, (plate 1,) and the other to the door or gate by means of the plate H, we obviate the friction that attends the use of the friction-roller in the end of the arm, or when left to rub against the door upon a friction-plate, and we also get rid of the noise of a friction-roller; and second, by the use of this stirrup we can so arrange the joint working in the end B¹ of the arm, (plate 1,) as to disconnect the arm from the stirrup, and thus leave the door to swing free of the spring, when that is desired. This arrangement of the arm B and stirrup F F is susceptible of a great variety of ornamental design. The tension of the spring is regulated by removing the arm B from the tenon of the mandrel C, and with a wrench or other suitable implement, the head C' of the mandrel is taken hold of and forced around until the tension of the spring is as strong as desired, when the arm is replaced and the tap or nut D is screwed down upon it.

Having thus fully described my invention, what I claim as new, and desire to secure by Letters Patent, is—

The combination of the box A, mandrel C, spring E, and plates D and K, with arm B and stirrup F, constructed and operating substantially as described and for the purposes set forth.

CYRUS W. SALADEE.
